UNITED STATES PATENT OFFICE

101,866

DESIGN FOR A VEHICLE AXLE END PLATE

George W. Geromanos, Rahway, N. J.

Application July 6, 1936, Serial No. 63,671

Term of patent 7 years

To all whom it may concern:

Be it known that I, George W. Geromanos, a citizen of the United States, residing at Rahway, in the county of Union and State of New Jersey, have invented a new, original, and ornamental Design for a Vehicle Axle End Plate, of which the following is a specification, reference being had to the accompanying drawing, forming part thereof.

Figs. 1 and 2 are elevation and plan views respectively of a vehicle axle end plate embodying my invention.

I claim:

The ornamental design for a vehicle axle end plate, as shown.

GEORGE W. GEROMANOS.
